FILL CAP

Edward Lyle Jones, Wilmette, Ill.

Application June 24, 1935, Serial No. 28,093
Renewed February 23, 1938

6 Claims. (Cl. 220—35)

My invention relates to safety closure caps for the open ends of pipes and the like and while suitable for other and varied uses is particularly applicable to the filling or dispensing conduits of gas and oil tanks whether located above or beneath the ground level and whether portable or stationary.

The primary object of the invention is the provision of a guard cap to prevent the mischievous or accidental introduction to the tank of foreign matter although when properly equipped with a sealing gasket it may be utilized as a closure to prevent leakage and consequent waste or the unauthorized drawing off of the fluid contents.

15. The caps of this type, usually called fill caps, have heretofore been screwed on or hinged to such pipes and in some instances have been associated with a removable padlock, but usually the attendant does not trouble to apply the padlock or 20. the key becomes lost which permits children at play or vandals to ruin the contents by dropping foreign matter into the filling pipe or even to pour water therein.

The provision of such fill caps with a separate 25 independent padlock of efficient make adds considerable expense and it is not unusual to find the fill cap without lock if the locks or keys become mislaid.

Tank wagons for gasoline or fuel oil often 30 have downwardly extending discharge pipes equipped with closure caps arranged to be screwed onto the open end. These being separate, the driver seldom screws them on after making a delivery, not appreciating the disadvantage of 35 road dust accumulating in the open end of the pipe or the serious aggregate loss from a continual leakage however small in volume.

By my invention I safeguard the filling pipes 40 against the introduction of foreign matter, the discharge pipes against leakage and dust and both against theft of the contents; the lock is formed as an integral part of the cap, self-contained, and not susceptible to becoming misplaced or lost; the lock cannot be readily picked or 45 forced; and the assembly is so arranged that it is substantially proof against being broken or forced off by a pry or other tool available to the trespasser. Moreover, the improved cap is readily applied to pipes already installed at filling stations and upon delivery trucks.

In order that the invention may be readily understood the same is hereinafter set forth in detail in connection with illustrative embodiments 55 adapted to particular purposes although it is ob-

vious that various modifications thereof fall within the spirit of the invention.

In the drawing,

Fig. 1 is a central longitudinal section through the delivery end of a dispensing pipe and applied cap, showing the lock in side elevation;

Fig. 2 is a side elevation of Fig. 1 taken at right angles thereto;

Fig. 3 is a vertical section on the line 3—3 of Fig. 1, showing the lock in engaged position;

Fig. 4 is a similar section through the lock in released position;

Fig. 5 is a central longitudinal section through a lock-equipped hinge cap;

Fig. 6 is an enlarged section on the line 6—6 of Fig. 5; and

Fig. 7 is a view similar to Fig. 5 through a lock-equipped swivel cap.

Having reference more in detail to the illustrative views of the drawing, the dispensing cap of Figs. 1 to 4 inclusive is shown as applied to the end of the delivery pipe 11 provided with an inwardly opening outwardly closing valve control 12 adjacent but spaced from its end. A nipple 13 is screwed into the threaded lower end of the pipe 11 with an interposed gasket 14. This nipple 13 is provided with a bifurcated lug comprising spaced ears 15, 15a between which is journaled the upper end of a lever 16 upon a pin 17 having fixed relation to the lever 16 by being squared, as indicated at 18, or forcibly driven thereinto to prevent angular movement. This pin 17 is freely rotatable within the ears 15, 15a and one end 17a is equipped with a spring 19 engaged therewith at 19a and engaging at 19b with the ear 17 whereby the lever 16 is spring-pressed into the position shown in full lines in Figs. 1 and 2 and may be swung into the position shown in dotted lines in Fig. 1 against the tension of the spring 19, where it will be held by the spring-pressed detent 16c engaging the projection 15c.

This lever 16 has projecting therefrom an operating handle 16a and extends as an arm in a curved direction downwardly at 16b and has formed integral therewith or rigidly attached thereto a cup-shaped cap 20 which receives, as shown at 20a, the lower end of the nipple 13. This cap contains a floating gasket 21 of suitable sealing material which is pressed against the lower end of the nipple by a compression spring 22; thus, under the combined influences of the springs 19 and 22, effectually sealing the nipple 13 against the entrance of dust or the escape of liquid which may by chance pass the valve 12.

Forming a part of the nipple, lever and cap 55;

assembly is a lock of the plunger type disposed within a lock barrel 23 cast integrally with the ear 15 or permanently assembled therewith and projecting to one side thereof. Within the barrel 23 is rigidly mounted as by welding a block 24 within which is guided a plunger bolt 25 of the lock, which bolt is arranged to reciprocate within the aperture 26 of the ear 15, as most clearly shown in Figs. 3 and 4, and when projected to extend into a recess 27 of the lever 16 when the parts are in the position shown in full lines in Fig. 1 and Fig. 4 with the recesses 26 and 27 in register, whereby to lock the lever with its cap against opening; whereas upon retraction of the plunger bolt 25 out of the recess 27 the parts are unlocked and the cap may be swung from its closed position on the nipple 13 to an open position, as indicated in dotted lines in Fig. 1, to enable the dispensing of liquid through the nipple 20 when the control valve 12 is opened.

Providing for the operation of the lock, the bolt 25 is surrounded by a coil spring 28 within the space between the block 24 and the ear 15, abutting at one end against the block and at the other end against a washer 29 which, in turn, is engaged by a stud 30 carried by the bolt 25. This spring normally presses the bolt into engagement with the recess 27, as shown in Fig. 3, while the same spring, upon the retraction of the bolt, as shown in Fig. 4, is nested within itself by reason of its formation as a truncated cone, thus conserving space.

The block 24 is formed upon its rear face as a cam at 31 upon which is adapted to ride a lug 32 projecting laterally from the bolt 25 and the bolt is rotated by the means hereinafter described to effect the longitudinal reciprocation of the bolt to lock and unlock the cap.

The outer end of the bolt 25 is provided with a head 33 bearing in relief upon its face a non-symmetrical configuration or design 34 which is adapted to be received within the same design formed in intaglio on the end of a key 35. This relief design 34 is but slightly spaced from the interior of the lock barrel 23 and the end of the key is provided with a marginal rim adapted to enter within said space for centering the proper key relative to the design and to prevent the engagement of the design configuration by a wrench, pliers or other tool for unauthorized operation of the lock. For the same purpose, the plunger head 33 and the design carried thereby are well within the open end of the barrel 23 to render access thereto impossible other than by the authorized key.

It will be readily understood that when in locked position if the key be inserted, as shown in Fig. 3, and rotated in a clockwise direction, the lug 32 will ride upwardly on the cam face 31 of the block 24, thus retracting the bolt 25 from the recess 27 against tension of the spring 28; whereas as when in the unlocked position, as shown in Fig. 4, the application of the key to the design 34 and turning of the same in a counterclockwise direction the lug 32 will be released from its position at rest upon the high point of the cam 31 and the bolt will be shot into the recess 27 by the reaction of the spring 28.

Having reference now to Figs. 5, 6 and 7 of the drawing, there are shown fill caps of usual types equipped with a lock. In Fig. 5 is shown a nipple 36 provided on one side with ears 37 and on the opposite side with ears 38. Between the ears 37 upon a pin 39 is journaled a cap 40 by a projecting arm 41 while at the opposite side an arm 42 of

the cap 40 is adapted to enter the space between the ears 38. The nipple 36 is adapted to be screwed upon or otherwise permanently secured to the pipe 43.

Formed integrally with or permanently secured to one of the ears 38 and projecting laterally therefrom is the lock barrel 23 containing the lock mechanism as hereinbefore described with reference to Figs. 1 to 4 inclusive, which need not be here repeated. In this instance, the lock bolt represented at 25a is beveled at its end, as indicated at 25b, for engagement by the beveled extremity 42a of the cap arm 42, which arm is apertured at 42b, as clearly shown in Fig. 6, for receiving the bolt 25a. It will be readily understood that the locking is here automatic upon the dropping of the cap arm 42 into the space between the ears 38, the retraction of the bolt 25a being accomplished by engagement of its beveled end 25b with the beveled end 42a of the arm 42. The unlocking is effected by the agency of the proper key in the manner hereinbefore described with reference to Figs. 1 to 4 inclusive.

The cap arm 41 may be provided with a lug 41a and the ears 37 with a lug 37a in order to prevent the cap from being swung beyond a dead center, whereby to insure that when the filling hose is removed from the entrance to the pipe 43 the cap will drop automatically to a closed locked position, thus preventing the same being inadvertently left open.

In Fig. 7 is shown the application of the present invention to a fill cap of the swivel type applied to the pipe 44. A nipple 45 is permanently secured to the pipe and is provided on opposite sides with the ears 46 and 47. The cap in this case is in the form of a nut 48 having a wrench-engaging portion 49 and adapted to be screwed into the open end of the pipe 44. This cap has spaced collars 50 and 51 in the annular space between which is received a circular connection 52 connecting the arms 53 and 54. The arm 54 of the cap is formed similarly to the arm 42 of Figs. 5 and 6 for locking engagement by the lock bolt. In this instance the annular space between the collars 50 and 51 and the play in the lock mechanism is sufficient to permit of the disengagement of the cap 48 from the threads of the pipe 44 by a wrench applied to the portion 49 but the disengaged cap cannot be removed from the open end of the pipe until the lock is operated to release the arm 54 whereupon the cap can be swung upwardly upon its hinge pivot 55. Obviously the wrench-engaging portion 49 may be omitted and the lower face of the cap may rest loosely upon the pipe end or may be provided with a skirt taking within or without the pipe end, as is illustrated in Fig. 5.

Obviously also the lugs 37a and 41a of Fig. 5 may be omitted or similar lugs may be applied to the ears 46 and the arm 53 of Fig. 7.

I claim:

1. In a closure for filling and dispensing pipes the combination with an inwardly opening outwardly closing valve disposed within the pipe adjacent its mouth, of a nipple connected to the pipe end outwardly of the valve and having a laterally projecting lug, a curved arm pivoted to the lug, a cup-shaped cap fixedly secured to the free end of the arm to swing to and from closing relation to the nipple, a rockingly supported gasket within the cap arranged to bear against the end of the nipple in the closed position of the cap, means pressing the arm and cap towards its closed position upon the nipple, and means yield-

ingly holding the arm and cap in open position free of the nipple end.

2. In a closure for filling and dispensing pipes, the combination with an inwardly opening outwardly closing valve disposed within the pipe adjacent its mouth, of a nipple screw connected to the pipe end outwardly beyond the valve and having an exterior laterally projecting lug, a curved arm pivoted to the lug, a cup-shaped cap fixedly secured to the free end of the arm to swing in an arc to and from enveloping relation to the nipple end, a floating spring-supported gasket within the cap arranged to bear against the end of the nipple in the closed position of the cap, a spring pressing the arm and cap towards its closed position about the nipple, and a spring detent yieldingly engaging the lug to hold the arm and cap when swung to open position free of the nipple end.

3. In a closure for filling and dispensing pipes, the combination with an inwardly opening outwardly closing valve disposed within the pipe adjacent its mouth, of a nipple connected to the pipe end outwardly of the valve and having a laterally projecting lug, a curved arm pivoted to the lug, a cup-shaped cap fixedly secured to the free end of the arm to swing to and from closing relation to the nipple, a rockingly supported gasket within the cap arranged to bear against the end of the nipple in the closed position of the cap, spring means pressing the arm and cap towards its closed position upon the nipple, and means releasably engaging the lug to hold the arm and cap in open position free of the nipple end in opposition to the spring closing means.

4. In a closure for filling and dispensing pipes, a bifurcated lug laterally projecting from the pipe end, a curved arm pivoted between the bifurcations of the lug, a cup-shaped cap secured to the free end of the arm to swing to and from enveloping relation to the open pipe end, a floating gasket within the cap arranged to bear

against the end of the pipe in the closed position of the cap, the pivot connection between the arm and the lug comprising a transfixing pin fixed against rotation in the arm and freely rotatable within the lug bifurcations as bearings, a spring coiled about one end of the pin with one end secured to the pin and the other end to the lug whereby the arm and cap are pressed towards the closed position, a spring-pressed detent upon the arm adjacent the lug, said detent arranged when the arm is swung to snap behind a portion of the lug whereby to hold the arm and cap in open position against its tendency to close under spring pressure.

5. In a closure for dispensing pipes, the combination with a primary valve therein spaced from the open end of the pipe, of an arm pivoted in fixed relation to said pipe, a cup-shaped cap carried by the free end of the arm to swing about the pivot as a center to and from enveloping relation to the pipe end, a rockingly supported gasket within the cap arranged to bear against the end of the pipe, means acting upon the arm to press the cap and gasket against the pipe end, and means for yieldingly holding the arm and cap with the gasket in open position free of the pipe end.

6. In a closure for dispensing pipes, the combination with an inwardly opening outwardly closing primary valve therein spaced from the open end of the pipe, of a bent arm pivoted in lateral fixed relation to said pipe, a cup-shaped cap carried by the free end of the arm to swing about the pivot as a center to and from closing relation to the pipe end, a gasket within the cap arranged to bear yieldingly against the end of the pipe, means acting upon the arm to hold the cap and gasket in closed relationship to the pipe end, and means for holding the arm and cap with the gasket in open position free of the pipe end.

EDWARD LYLE JONES.
